UNITED STATES PATENT OFFICE.

PATRICK KEEGAN, OF FALL RIVER, MASSACHUSETTS, ASSIGNOR TO DRAPER CORPORATION, OF HOPEDALE, MASSACHUSETTS, A CORPORATION OF MAINE.

FILLING-DETECTING DEVICE FOR LOOMS.

Application filed February 11, 1924. Serial No. 691,939.

To all whom it may concern:

Be it known that I, PATRICK KEEGAN, a citizen of the United States, and a resident of Fall River, county of Bristol, State of Massachusetts, have invented an Improvement in Filling-Detecting Devices for Looms, of which the following description, in connection with the accompanying drawing, is a specification, like characters on the drawing representing like parts.

This invention relates to a filling detecting device for looms such as commonly employed to detect the exhaustion or breakage of the filling and thereupon effect a change in the operation of the loom. Such devices are usually provided in connection with automatic weft replenishing looms either to effect the stoppage of the loom or the replenishment of the filling whenever the filling breaks or becomes exhausted.

The device comprises a so-called fork carried by a slide and adapted to cooperate with a hook on the usual vibrating weft hammer of the loom. So long as the filling is properly laid in front of the fork the fork is rocked at each beat-up of the lay into a position where it cannot engage the hook. If, however, the filling is absent from in front of the filling fork upon the beat-up, due to breakage or exhaustion, then the filling fork engages the hook and the slide is carried forward with the weft hammer and this motion is utilized to effect the desired change in the operation of the loom such as the stoppage of the loom or the automatic replenishment of the filling.

Lint, waste and broken filling ends not infrequently accumulate during the operation of weaving to such an extent as occasionally to prevent the proper cooperation of the filling fork and hook either by preventing the filling fork from engaging the hook or by maintaining the filling fork in engagement with the hook. The object of the present invention is so to construct the filling detecting device as to prevent such an undesired accumulation of lint, waste and filling ends and to ensure the proper cooperation of the filling fork and hook and

further to enable the condition of the filling fork and hook to be observable at all times by the operator.

The nature and object of the invention will appear more fully from the accompanying description and drawings and will be particularly pointed out in the claims.

In the drawings:

Fig. 1 is a side elevation of a filling detecting device embodying a preferred form of the invention;

Fig. 2 is a top plan view of the construction shown in Fig. 1;

Fig. 3 is a view in vertical cross section taken on the line 3—3 Fig. 2 and showing the filling fork engaging the hook carried by the weft hammer;

Fig. 4 is a detail elevation of a modified form of the invention.

The general construction and operation of a filling detecting mechanism of this nature is so well known and familiar to those skilled in the weaving art that it will only be necessary here to illustrate and describe those parts particularly concerned with the present invention.

The slide 1 is usually mounted on the breast beam of the loom so as to slide forwardly and rearwardly thereon and is yieldingly held projected rearwardly toward the lay. This slide terminates at the rear in a pair of transversely separated arms 2. The filling fork comprises a body 4 fulcrumed on a stud 5 extending between and mounted in the rear end of the arms 2. The tines 6 of the fork extend downwardly from the body and the tail 7 which is loop-shaped extends forwardly from the body. The usual vibrating weft hammer 8 of the loom projects upwardly between the arms 2 which thus straddle the weft hammer and this weft hammer carries pivoted to its upper end at 9 a hook 10 which rests upon a bar 11 extending transversely between the arms 2.

If the filling is properly laid by the shuttle it will be carried by the lay, and usually by a grid-like device supported on the lay, against the tines 6 of the fork thus rocking the fork on its stud 5 and raising the

tail 7 so that it cannot catch upon the hook 10. If, however, the filling is broken or exhausted there is nothing to swing the fork when the lay beats up and the fork will remain in the position shown in Fig. 3 in engagement with the hook 10. Consequently when the weft hammer 8 swings forwardly the filling fork and with it the slide 1 will be carried forwardly and this movement utilized to effect the desired change in operation of the loom.

Owing, as has already been pointed out, to the occasional accumulation of lint, waste or broken filling ends, the tail 7 of the filling fork may not effect the desired cooperation with the hook 10. Such an accumulation may prevent the tail 7 from catching on the hook or it may cause these parts so to adhere together as to prevent their separation. This is prevented by the present invention.

For this purpose the arms 2 at their rear portions are extended upwardly, preferably in the generally triangular shape 12. The arms 2 with the triangular extensions 12 are connected at the rear by the wall 13. The space between the triangular extensions 12 in front at the top is preferably enclosed by a transparent and preferably removable window. For this purpose the top front edges 14 are grooved at their inner sides and a plate 15 of glass, celluloid or other transparent material is slid into these grooves.

There is thus formed a hood enclosing at the top and the rear the space between the arms of the slide in which the fork swings. Thus accumulation of lint, waste or filling ends in the vicinity of the filling fork and hook is effectually prevented. The transparent window enables the operator at all times to have an unimpeded view of the fork and the hook and thus to observe its condition. The removable feature of the window which is effected by sliding the plate 15 upwardly out of the hood in the grooves enables the operator to have free access to the filling fork and hook.

A modified form of the invention is shown in Fig. 4 which illustrates a hood of the character above described adapted to be applied to a usual type of filling fork slide. This construction comprises vertical walls 16 and a rear wall 17 which desirably are formed integral and may be cast or formed of sheet metal, the side wall 16 being adapted to be secured to the slide arms 2 by screws 18 or other suitable fasteners. The hood comprises a suitable closure or cover 19 which may be made of any suitable material and which, as illustrated in Fig. 4, is hinged at its upper end to the rear wall 17 of the cover. Desirably the cover or closure 19 is made in whole or in part of a

transparent material in order that the operator may at any time observe the condition of the filling fork.

There is thus presented a very simple and effective construction by which the character of the filling detecting device is much improved and danger from accumulation of lint waste or filling ends is prevented.

Having thus described the invention, what is claimed as new, and desired to be secured by Letters Patent, is:

1. A filling detecting device for a loom comprising a slide terminating at its rear end in transversely separated arms adapted to straddle the usual hook on the vibrating weft hammer, a filling fork fulcrumed between and in said arms and having a forwardly extending tail to cooperate with the hook and downwardly extending tines, and a hood enclosing at the top and rear the space between said arms in which the fork swings.

2. A filling detecting device for a loom comprising a slide terminating at its rear end in transversely separated arms adapted to straddle the usual hook on the vibrating weft hammer, a filling fork fulcrumed between and in said arms and having a forwardly extending tail to cooperate with the hook and downwardly extending tines, and a hood having a transparent window and enclosing at the top and the rear the space between said arms in which the fork swings.

3. A filling detecting device for a loom comprising a slide terminating at its rear end in transversely separated arms adapted to straddle the usual hook on the vibrating weft hammer, a filling fork fulcrumed between and in said arms and having a forwardly extending tail to cooperate with the hook and downwardly extending tines, and a hood enclosing at the top and rear the space between said arms in which the fork swings the said hood presenting in front at the top a downwardly inclined, removable, transparent window.

4. A filling detecting device for a loom comprising a slide terminating at its rear end in transversely separated arms adapted to straddle the usual hook on the vibrating weft hammer, a filling fork fulcrumed between and in said arms and having a forwardly extending tail to cooperate with the hook and downwardly extending tines, and a hood enclosing at the top and rear the space between said arms and having a removable closure.

5. A hood for enclosing at the top and rear the space between the rearwardly extending arms of a filling fork slide comprising walls extending upwardly from the respective slide arms, a connecting rear wall and a removable front wall.

6. A hood for enclosing at the top and

rear the space between the rearwardly extending arms of a filling fork slide comprising walls extending upwardly from the respective slide arms, a connecting rear wall, 5 a removable front wall and means for securing the upwardly extending walls to said slide arms.

7. A hood for enclosing at the top and rear the space between the rearwardly extending arms of a filling fork slide comprising

10 ing vertical substantially triangular walls extending upwardly from the respective slide arms connected by an integral rear wall and a removable front wall and means for securing said upwardly extending walls 15 to said slide arms.

In testimony whereof, I have signed my name to this specification.

PATRICK KEEGAN.
